UNITED STATES PATENT OFFICE.

ARLANDO M. VANDIVIER, OF INDIANAPOLIS, INDIANA.

SEPARATOR STRIP FOR CONCRETE FLOOR CONSTRUCTION.

Application filed February 29, 1924. Serial No. 695,835.

To all whom it may concern:

Be it known that I, ARLANDO M. VANDIVIER, a citizen of the United States, residing at Indianapolis, in the county of Marion and State of Indiana, have invented a new and useful Separator Strip for Concrete Floor Constructions, of which the following is a specification.

My invention relates to pattern and guide strips for plastic work and particularly for use in forming "terrazzo mosaic" floor, walls, etc.

One of the objects of my invention is to provide a guide strip which, when placed in position will remain standing until the material has been poured.

Another object of my invention is to provide a guide strip which is provided with improved means for locking the strip in the plastic composition.

For the purpose of disclosing my invention, I have illustrated one embodiment thereof in the accompanying drawings, in which—

Fig. 1 is a sectional view of a floor having one of my strips formed therein, the material being ready to receive the finishing layer of plastic material;

Fig. 2 is a side elevation of a strip embodying my invention;

Fig. 3 is a plan view, and

Fig. 4 is a perspective view.

In the embodiment of the invention illustrated I provide a strip 1 of flat metal, preferably brass, and thin enough to be flexible. This strip is provided at its top with a straight edge 2 which forms the guiding edge and towards its bottom has pushed or struck up, a series of tongues 3 which are bent to extend transversely of the strip alternately on opposite sides of the strip and have their bottom edges 4 in the same plane as the bottom edge of the strip. The striking up or forming of these tongues leaves in the body of the strip, openings 5 and the shape of the tongue is such that one wall 6 of the opening is provided with a projection

7 forming a top shoulder 8. This shoulder is below the plane of the top of the tongue 3.

In use the strips are placed in position 50 upon the usual concrete and gravel floor bed 9, after which the base filler 10 is poured between the strips.

It will be noted that, due to the fact that the tongues 3 extend from opposite sides of 55 the strip, they form a supporting means for maintaining the strip in vertical position and also provide a locking means for holding the strip in place when the concrete or plastic material is poured. When the concrete 60 is poured in place it flows in and through the openings 5 and the shoulders 8 form additional locking means to prevent vertical displacement of the ribs even though the concrete 65 does not come above the top 65 of the tongues 3.

After the filler 10 is placed in position, the finishing filler may be poured until it is level with the top of the strips. Preferably 70 before this finishing filler is poured the concrete or plastic material 10 is allowed to harden or set so that when the finishing filler is poured in position the top or straight edge 2 of the strip is held sufficiently rigid to form a guide for the tool used in leveling off the 75 floor.

I claim as my invention:

A pattern and guide strip comprising a strip of flat metal having a straight edge and having a plurality of tongues each 80 struck up to extend transversely of the strip and leave an opening in the strip, one wall of which is provided with an offset shoulder in a plane below the plane of the top of the tongue, the bottoms of said tongues being in 85 the same plane as the bottom of the strip and the tongues being adapted to project from opposite sides of the strip.

In witness whereof, I have hereunto set 90 my hand at Indianapolis, Indiana, this 8th day of February, A. D. one thousand nine hundred and twenty four.

ARLANDO M. VANDIVIER.
